SPINDLE ATTACHMENT FOR A SPINNING FRAME

Joseph P. McHugh, Scranton, Pa., assignor, by
mesne assignments, to Industrial Machine
Corporation, a corporation of Delaware

Application October 1, 1936, Serial No. 103,589

26 Claims. (Cl. 118—8)

This invention relates to a spindle attachment for a spinning frame and is particularly well adapted for so-called multiple down ring spinning machines.

5 In its broader aspects, the invention comprehends a spindle attachment embodying a spindle whirl and brake mechanism so arranged that the spindle whirl can be moved laterally away from the driving belt and the brake concurrently applied to the whirl.

10 In its more specific aspect, the invention comprehends a spindle attachment in which the spindle and whirl move laterally with respect to the belt in a plane perpendicular to the line of 15 travel of the belt, and the lateral movement of the spindle functions to apply the brake in such manner that the further the spindle is moved, the greater will be the application of the brake.

15 Various types of swing spindle attachments for spinning frames have heretofore been devised, and in such prior art spindles it is usual to provide some braking means for the spindle whirl. The brakes, however, often become worn, and there is lack of uniformity of application of the 20 brake to the whirl. Through the medium of the present invention, the difficulties encountered in the prior art practices are obviated, and a structure is provided which insures the positive application of the brake throughout the life of the 25 device.

30 Other and more detailed objects will become apparent as the description of the invention proceeds, which description will be given in connection with the accompanying drawing, where- 35 in:

Figure 1 is a detailed plan view of the swing spindle attachment with the spindle removed and parts broken away for clearness;

Figure 2 is a side elevational view taken from 40 the front of the spindle attachment;

Figure 3 is an end elevation taken from the left-hand side of Figure 2; and

Figure 4 is a detailed fragmentary view with parts shown in section.

45 Referring to Figure 1, the spindle rail is formed in two parallel tubular elements 1 and 2 which extend longitudinally of the spinning frame in a conventional manner. The spindle attachment is adapted to be firmly clamped in fixed relation to the members 1 and 2 through the medium of the clamping bolt 3 (Figure 2) and the clamping member 4 adapted to be positioned below the parallel tubular members 1 and 2. The upper end of the bolt 3 extends through the fixedly mounted 50 base member 5 as shown at 6. The base member

5 supports all of the operative elements of the spindle and brake. The base 5 is provided at one side with the upwardly projecting flange 7 carrying at the forward side of the base 5 the arm 8 which is provided with a spring seat 9 having the adjustable screw 10 for controlling the degree of tension placed upon the spring 11 which functions in a manner hereinafter described.

10 The opposite end of the base member 5 is provided with a flange 12. The flange 12 carries a bearing pin 13 adapted to pivotally support the lower end 14 of a stop motion rod 15. This stop motion rod is designed to have pivotal motion about the pivot bearing 13 in a manner comparable to that of the stop motion rod shown and described in my Patent No. 2,044,621, issued June 16, 1936, to which reference may be made for the detailed character of the stop motion mechanism associated with the rod 15.

15 Pivotedly supported between the flanges 7 and 12 of the base member 5 is the U-shaped yoke 16. 20 This U-shaped yoke 16 is provided at the free end of each of the legs thereof with an integral upstanding bracket member 17. This yoke 16 is pivotally supported on the base member 5 through the medium of the adjustable bearing member 18 25 (see Figure 2) having the conical bearing surface 19 fitting into a complementary recess 20 in the yoke and by the similar bearing provided by the screw 13 at the opposite end of the base 5 shown in detail in Figure 4, wherein it will be observed 30 that the screw 13 is likewise provided with a conical bearing end 21 fitting into the complementary recess 22 of the yoke member 16. The screw 13 additionally carries the adjusting nuts 35 23 for accommodating the pivotal bearing 14 of the stop motion rod 15, regardless of the position of adjustment of the bearing screw 13, and for locking the bearing screw 13 in any particular position of adjustment in the threaded opening 24 of the flange 12. A similar locking nut 25 is 40 provided for locking the bearing screw 18 in any particular position of adjustment with respect to the threaded opening 26 in the flange 7.

45 It will be observed from the foregoing description that the yoke member 16 is adapted to have a limited rocking movement about a horizontal axis formed by the bearing screws 13 and 18. The right-hand bracket arm 17 on the yoke 16, as shown in Figure 1, is provided with a seat 26 for one end of the spring 11. The spring 11 thus 50 functions to press the upper ends of the bracket arms 17 away from the arm 8 carried by the base member 5 and toward the spindle driving belt 27 of the frame.

The yoke 16 carries a spindle base 28. This spindle base 28 is supported by the complementary bearing screws 29, one of which extends through the top of each of the bracket members 17. The bearing screws 29 are adapted to be locked in any position of adjustment through the medium of the locking nuts 30. It is thus apparent that the spindle supporting base 28 is adapted to have limited rocking movement with respect to the yoke 16, which in turn is adapted to have limited rocking movement with respect to the base 5. The spindle base 28 is provided with the opening 31 in which the spindle 32 having the conventional whirl 33 is adapted to be clamped through the medium of the spring 34 and clamp nut 35. The spindle base 28 additionally carries the projecting arm 36 adapted to extend into the path of movement of the stop motion rod 15 when the latter is released through the breaking of a thread 15 and swings outwardly about its pivot 14.

It will be apparent that when the stop motion rod 15 contacts the arm 36 of the spindle base 28, the yoke 16 will swing upwardly with respect to the base 5, and the spindle base 28 carrying the spindle 32 will be caused to move laterally away from the belt 27 to free the whirl 33 therefrom. When the stop motion rod 15 is restored to operative position, the spring 11 functions to return the yoke 16 to normal position with the whirl 33 in driving engagement with the belt 27.

Coming now to a specific description of the means for controlling the movement of the spindle and for applying the brake to the whirl, it will be observed that the spindle base 28 is additionally provided with a bearing lug 37 (see Figure 3) and that the flange 12 of the base 5 carries a further bearing screw 38. A bearing bolt 39 extends through the bearing lug 37, and a link 40 has its respective ends pivotally mounted on the bearing screw 38 and bearing bolt 39. It will be observed by reference to Figure 3 that the flange 12 of the base member 5, a bracket member 17 of the yoke 16, the spindle supporting base 28, and the link 40 together form a parallelogram, the four corners of which are pivotally connected. The base member 5 and the flange 12 are, however, fixedly secured to the spindle supporting rail and, therefore, the spindle supporting base 28 is adapted to swing toward and away from the belt 27 but is always maintained in a horizontal plane with the spindle 32 carried thereby always in a vertical position.

The spindle base 28 further carries in fixed relation thereto the upstanding arm 41, which arm is adapted to partake of the same movement as the spindle base member 28. The arm 41 carries at its upper end a bearing bolt 42. A brake member indicated generally at 43 is pivotally mounted on the bearing bolt 42. The brake member 43 is generally U-shaped with one leg 44 of the U extending clear down to the bearing 38 and being bifurcated to accommodate the bearing 38 as shown at 45 in Figure 3. The other leg 46 of the U-shaped brake 43 extends downwardly to a short distance below the pivotal mounting 42 and carries at its lower end the frictional brake contact member 47.

The action of the brake is as follows: When the stop motion rod 15 is released and moves the spindle base 28 laterally with respect to the base member 5, the bearing 42 is likewise moved laterally and downwardly with respect to the base member 5. This movement of the bearing 42 causes the brake member 43 to be moved about the bearing 42, and because of its relationship to

the bearing 38, the brake shoe 47 is adapted to be forced into contact with the whirl 33. It is at once apparent that the greater the movement of the base 28, the greater will be the force applied to the brake shoe 47 and thereby to the whirl 33 5 of the spindle.

Briefly summarizing, the operation of the device is as follows: When a thread breaks, the stop motion rod 15 swings about its pivot 14 and applies force through the arm 36 to the spindle base 10 28. This swings the upper ends of the bracket arms 17 of the yoke 16 on the bearing screws 13 and 18. The spindle base 28 in turn rocks slightly on the bearing screws 29, but this rocking movement is controlled by the link 40 interconnecting 15 the bearing 38 carried by the spindle base 28 and the bearing 38 carried by the bracket base 5, so that the spindle base 28 moves laterally and downwardly with respect to the base 5 but is always maintained in a horizontal position. This 20 movement of the spindle base 28 likewise effects movement of the brake bearing 42 and applies the brake in the manner above specifically set forth.

From the foregoing detailed description, it will 25 be apparent that the applicant has provided a novel spindle attachment for a spinning frame, through the medium of which the spindle base is swung away from the belt on horizontal rather than vertical pivots, and a structure whereby the 30 brake is positively applied to the spindle whirl through mechanical motion that counteracts the movement of the spindle. It will be additionally observed that the respective bearings are adjustable, permitting slight relative movement between the respective parts of the spindle attachment and furthermore making it possible to immediately compensate for wear at any time.

Having thus described my invention, what I 40 claim is:

1. A spindle attachment for spinning frames comprising a base adapted to be fixedly attached to the spinning frame, a spindle supporting member mounted for limited pivotal movement with respect to said base, a movable brake member 45 associated with said fixed base and said movable spindle supporting member, a spindle mounted on said spindle supporting member, a whirl for driving said spindle, and means operative upon movement of said spindle supporting member with respect to said fixed base for actuating said brake to stop said whirl and oppose further movement of said spindle supporting member.

2. A spindle attachment for spinning frames comprising a base member adapted to be fixedly 55 attached to the spinning frame, a spindle supporting member adapted to have limited pivotal movement with respect to said base member, a spindle carried by said spindle supporting member, a whirl for driving said spindle, a brake 60 member pivotally supported by said spindle supporting member, and means associated with said brake adapted to resist movement of said spindle supporting member beyond the point of contact with said brake.

3. A spindle attachment for spinning frames comprising a base adapted to be fixedly attached to the spinning frame, a spindle supporting member mounted for limited pivotal movement with respect to said base about a horizontal axis, a 70 movable brake member associated with said fixed base and said movable spindle supporting member, a spindle mounted on said spindle supporting member, a whirl for driving said spindle, and means operative upon movement of said 75

- spindle supporting member with respect to said fixed base for actuating said brake to stop said whirl and oppose further movement of said spindle supporting member.
- 5 4. A spindle attachment for spinning frames comprising a base member adapted to be fixedly attached to the spinning frame, a yoke mounted for limited pivotal movement with respect to said base, a spindle supporting member pivotally connected to said yoke, and means for causing said spindle supporting member to occupy a horizontal position during relative movement between said spindle supporting member and said base.
- 10 5. A spindle attachment for spinning frames comprising a base member adapted to be fixedly attached to the spinning frame, a spindle supporting member adapted to have pivotal movement with respect to said base member about a horizontal axis, and means interconnecting said base and spindle supporting member for maintaining said spindle supporting member in a horizontal position throughout the limits of its relative movement with respect to said base.
- 15 6. A spindle attachment for spinning frames comprising a base member adapted to be fixedly attached to the spinning frame, a spindle supporting member adapted to have pivotal movement with respect to said base about a horizontal axis, a spindle carried by said spindle supporting member, a whirl for driving said spindle, a brake associated with said base and spindle supporting member, and means interconnecting said base and spindle supporting member adapted to maintain said spindle supporting member
- 20 30 in horizontal position throughout the limits of its relative movement with respect to said base.
- 35 7. A spindle attachment for spinning frames comprising a base member adapted to be fixedly attached to the spinning frame, a spindle supporting member adapted to have pivotal movement with respect to said base about a horizontal axis, a spindle carried by said spindle supporting member, a whirl for driving said spindle, a brake associated with said base and spindle supporting member, means interconnecting said base and spindle supporting member adapted to maintain said spindle supporting member in horizontal position throughout the limits of its relative movement with respect to said base, and means
- 40 45 50 effective upon movement of said spindle supporting member relative to said base for actuating said brake.
- 55 8. A spindle attachment for spinning frames comprising a spindle having a whirl, and supporting means for said spindle including a parallelogram constructed and arranged to cause swinging movement of said spindle and whirl about a horizontal axis.
- 60 9. A spindle attachment for spinning frames comprising a spindle having a whirl, and supporting means for said spindle constructed and arranged to cause swinging movement of said spindle and whirl about a horizontal axis while maintaining the axis of said spindle extending truly vertically.
- 65 10. A spindle attachment for spinning frames comprising a spindle having a whirl, and supporting means for said spindle including a movable parallelogram.
- 70 11. A spindle attachment for spinning frames comprising a spindle having a whirl, supporting means for said spindle constructed and arranged to cause movement of the spindle and whirl about a horizontal axis, and pivotally supported
- 75 brake means for said spindle connected to the spindle supporting means to be moved into engagement with the spindle whirl by movement of said supporting means.
12. A spindle attachment for spinning frames comprising a spindle having a whirl, and supporting means for said spindle constructed and arranged to cause swinging movement of said spindle and whirl about a horizontal axis while maintaining the axis of said spindle extending truly vertically, and pivotally supported brake means for said spindle connected to the spindle supporting means to be moved into engagement with the spindle whirl by movement of said supporting means.
13. A spindle attachment for spinning frames comprising a spindle having a whirl, supporting means for said spindle including a movable parallelogram, and pivotally supported brake means for said spindle connected to the spindle supporting means to be moved into engagement with the spindle whirl by movement of said supporting means.

- comprising a main base fixed to the spinning frame, a spindle having a whirl, a spindle base, means pivotally connected to the main base and the spindle base to form therewith a parallelogram supporting the spindle for lateral and downward movement while maintaining the spindle axis extending vertically, a brake for said whirl, means for pivotally supporting the brake on the spindle base, and means operatively connecting the brake to the fixed main base for causing movement of the spindle base to effect application of the brake to the whirl.
21. A spindle attachment for spinning frames, comprising a spindle, and supporting means for said spindle constructed and arranged to cause swinging movement of said spindle about an axis which extends in a direction normal to the spindle axis while maintaining the axis of said spindle extending in its original direction.
22. A spindle attachment for spinning frames comprising a spindle, supporting means for said spindle constructed and arranged to cause swinging movement of said spindle about an axis which extends in a direction normal to the spindle axis while maintaining the axis of said spindle extending in its original direction.
23. A spindle attachment for spinning frames comprising a spindle having a whirl, supporting means for said spindle and whirl constructed and arranged to cause swinging movement of said

spindle and whirl about an axis which extends in a direction normal to the spindle axis while maintaining the axis of said spindle extending in its original direction, a movably supported brake, and means for causing movement of the spindle supporting means to effect movement of the brake into engagement with the spindle whirl.

24. A spindle attachment for spinning frames comprising a spindle having a whirl, supporting means for said spindle including a movable parallelogram, a movably supported brake, and means for causing movement of the spindle supporting means to effect movement of the brake into engagement with the spindle whirl.

25. A spindle attachment for spinning frames comprising a spindle having a whirl, supporting means for said spindle including a movable parallelogram, and a brake engageable with the spindle whirl upon movement of said supporting means.

26. A spindle attachment for spinning frames comprising a spindle having a whirl, supporting means for said spindle constructed and arranged to cause swinging movement of said spindle about an axis which extends in a direction normal to the spindle axis while maintaining the axis of said spindle extending in its original direction, and a brake engageable with the spindle whirl upon movement of said supporting means.
